SCISSORS

Perry McCaw, Sappho, Wash.

Application November 25, 1936, Serial No. 112,792

3 Claims. (Cl. 30—13)

This invention relates to scissors and has for an object to improve the construction of scissors of the general type described in my Patent No. 1,433,391 issued October 24, 1922.

5 A specific object of the present invention is to provide in the flat face of the blade carrying shanks of the scissors, thumb and finger receiving recesses across which extend resilient blade latches having bent ends extending through openings in the shanks and in the blades whereby the blades may be quickly and easily removed and detached without the use of tools, and with minimum manual exertion.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a front elevation of a pair of scissors constructed in accordance with the invention.

Figure 2 is a cross sectional view taken on the line 2—2 of Figure 1.

Figure 3 is a cross sectional view taken on the line 3—3 of Figure 1.

Figure 4 is a longitudinal sectional view through one of the shanks and showing a blade with reversible cutting edges secured therein.

Figure 5 is a detail longitudinal sectional view taken on the line 5—5 of Figure 4.

Figure 6 is a detail cross sectional view taken on the line 6—6 of Figure 4.

Referring now to the drawing in which like characters of reference designate similar parts in the various views, 10 designates the shanks of the scissors which terminate in handles 11, the shanks being pivotally connected together at their crossing by a pivot pin 12.

A recess 13 is formed in the inner edge of each shank and is disposed at an angle to the flat face of the shank as best shown in Figure 2 and receives a blade 14 having two cutting edges 15. The blade is tapered at one end to conform to the contour of the shank, as best shown in Figure 4, and at the opposite end is provided with a lug 16 which is received in a notch 17 of substantially the same shape as the lug.

In order that each blade 14 may be retained in its recess a thumb and finger receiving recess

18 is provided in the outer face of the shank 10. A latch 19, best shown in Figure 3, and preferably formed of spring wire, is secured at one end to the shank by forming a groove 20 in the shank and upsetting the material of the shank on opposite sides of the groove to provide tabs 21 which overlap the latch and clamp the latch to the shank. The latch extends across the recess 18 and beyond the recess is received in a groove 22 so that the latch lies flush with the face of the shank. The tip end of the latch is bent laterally to provide a hook 23 which is received in an opening 24 formed in the bottom of the groove 22 and in an opening 25 formed in the blade 14.

In operation by inserting the thumb or finger in the recess 18 of the shank underneath the latch 19 the latter may be deformed outwardly to disengage from the blade 14 whereupon the blade may be removed from its recess 13 and reversed to present the other cutting edge to the work when desired. By virtue of the latch lying flush with the outer side of the shank no obstructions will be presented during the cutting operation while at the same time the shape of the latch and the recess 18 underneath it permit of the latch being operated easily and quickly by the fingers without the use of tools.

From the above description it is thought that the construction and operation of the invention will be fully understood without further explanation.

What is claimed is:

1. A pair of scissors including crossed shanks pivoted together at their crossing and terminating in handles, blades carried by said shanks, thumb and finger receiving recesses in the outer faces of the shanks, and spring latches carried by the shanks and extending across said recesses flush with the outer faces of the shanks and terminally removably engaged in said shanks and said blades.

2. A pair of scissors including crossed shanks pivoted together at their crossing and terminating in handles, each shank having a longitudinal recess in its inner edge, a double edged blade in said recess conforming to the shape of the shank, said blade and said shank being provided with registering openings, a thumb and finger recess in the outer face of the shank, and a spring wire latch fixed at one end to the shank and extending across said recess and into said registering openings to removably secure the blade to the shank.

3. A pair of scissors including crossed shanks pivotally connected together at their crossing and

terminating in handles, each shank being provided with a longitudinal recess in its inner edge, a double edged blade in the recess having a lug at one end, there being a recess in the shank receiving the lug, said blade and said shank having registering openings formed therein, a spring wire latch having one end fixed to the shank by tabs struck from the outer face of the shank and overlapping the latch, there being a

thumb and finger receiving recess in the outer face of the shank across which said latch projects, and an angularly bent extremity on the latch engaged in said registering openings, there being a groove in the outer face of the shank receiving the latch and permitting the latch to lie flush with the outer face of the shank. 5
